UNITED STATES PATENT OFFICE.

WILLIAM G. WILSON, OF WEST NEW BRIGHTON, NEW YORK.

RAIL JOINT.

Application filed June 2, 1924. Serial No. 717,362.

To all whom it may concern:

Be it known that I, WILLIAM G. WILSON, a citizen of the United States, residing at West New Brighton, Staten Island, in the 5 county of Richmond and State of New York, have invented new and useful Improvements in Rail Joints, of which the following is a specification.

This invention relates to rail joints and 10 is an improvement over my application Serial No. 635,682 allowed December 13th, 1923.

The principal object of the invention is the provision of a rail joint whereby the 15 creeping of the rail caused by the direction of travel of the rolling stock thereover will cause the rails to be moved into closer contact with the joint and their supporting ties.

20 Another object of the invention is to provide a rail joint which will creep with the rails for a predetermined distance, and after reaching the limit of movement, will coact with the ties to effect a tighter joint.

25 With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of a pair of rails provided with my improved rail joint 35 prior to creeping of the same.

Figure 2 is a similar view but showing the position of the parts after the rails have crept a predetermined distance.

Figure 3 is a bottom plan view.

40 Figure 4 is a transverse sectional view on the line 4—4 of Figure 1.

Figure 5 is a perspective view of one of the joint sections.

Referring more particularly to the drawing, the reference numerals 10, 10 designate the meeting ends of a pair of rails which are connected together by a joint 11 of the construction shown in my co-pending application above referred to. The 45 rail joint 11 includes a pair of identical sections 12 and 13, each of which comprises an angle bar 14 having a chair 15 arranged centrally thereof and depending therefrom. Each chair 15 includes end walls 16 and 50 side walls 17. The end walls 16 are each formed with a prong 18 having a lower

horizontal face 19 and a beveled or inclined face 20 which meets the horizontal face to form a suitable point. The two sections are secured to the rail joints by the usual bolts 60 and nuts 21 and the rails are held down upon the ties 22 by spikes 22'. A bolt 23 passes through the side walls 16 when the chairs are in their respective positions and serves to anchor the sections beneath the 65 rails centrally of the joint.

When the joint sections are applied, the same are positioned so that the chairs depend between two ties, the ties being spaced 70 so that the prongs are arranged in close proximity thereto as shown in Figure 1 of the drawing whereby any tendency of the joint to creep in either direction will only cause the prongs at one end of the chairs to penetrate the sides of the ties. When the prongs penetrate the ties, the inclined or beveled face 20 will tend to set-up a wedging action sufficient to cause the rails to move into closer contact with the ties 75 and will also cause the joint sections to bear down into closer engagement with the rails.

80 From the foregoing description, it will be seen that when the rails creep by reason of the rolling stock traveling in one direction, the joint may only move a predetermined distance wherein it will stop as the end walls 16 and the prongs 18 will co-act with the ties to form a barrier. In Figure 85 1 of the drawing, there is shown a view prior to the creeping of the joint and in Figure 2 a view of the joint after the same has crept due to the rolling stock travelling in the direction of the arrow. It will, of course, be understood that if the travelling of the rolling stock was in an opposite 90 direction to the arrow, the prongs on the opposite ends of the chairs would penetrate 95 the opposite ties.

100 While I have described what I deem to be the most desirable embodiment of my invention, it is obvious that many of the details may be varied without in any way departing from the spirit of my invention, and I therefore do not limit myself to the exact details of construction herein set 105 forth nor to anything less than the whole of my invention limited only by the appended claims.

110 What is claimed as new is:—

1. The combination with the meeting ends of a pair of rails, a joint therefor including a pair of sections each having a

depending chair intermediate its ends, ties for supporting said rails, said chairs interposed between two of the ties, and means carried by said chairs for penetration in the ties upon the creeping of the joint in either direction.

2. The combination with the meeting ends of a pair of rails, of a joint therefor including a pair of sections each having spaced depending walls, ties for supporting said rails, a prong formed on each of said walls, said walls being disposed in close proximity to said ties, whereby creeping of the rails in either direction will cause cer-

tain of the prongs to enter one of the ties 15 to move the parts into closer contact with the ties.

3. The combination with the meeting ends of a pair of rails, supporting ties therefor, means for connecting the ends of 20 said rails together, and means for moving said rails into closer contact with said ties upon the creeping of said rails in either direction.

In testimony whereof I have affixed my 25 signature.

WILLIAM G. WILSON.
